UNITED STATES PATENT OFFICE.

WORTHINGTON S. TELFORD, OF DULUTH, MINNESOTA.

SHOE.

No. 902,929.

Specification of Letters Patent.

Patented Nov. 3, 1908.

Application filed January 20, 1908. Serial No. 411,764.

To all whom it may concern:

Be it known that I, WORTHINGTON S. TELFORD, a citizen of the United States, residing at Duluth, in the county of St. Louis and 5 State of Minnesota, have invented certain new and useful Improvements in Shoes, of which the following is a specification.

This invention relates to an attachment for shoes, which will act as a permanently 10 secured shoe horn and which can be drawn out sufficiently to render it easy to insert the heel of the foot in the shoe, as will be hereinafter more fully described and pointed out in the specification and claims.

15 More particularly this invention is adapted to low-cut or Oxford shoes, although obviously it can be used on shoes of other forms if desired.

In operation this invention serves to produce 20 a stiff upper edge above the counter at the heel when in superior position, and, after the foot has been inserted in the shoe, may be pushed down, leaving the portion above the counter flexible.

25 Among the objects of my invention are simple and inexpensive construction, greater effectiveness in operation, and a device which is always ready for use.

In the accompanying drawings forming 30 part of this specification, Figure 1 is a side view of my invention, showing the attachment which I have chosen to term a "slide" in position when not in use; Fig. 2 is a longitudinal side view in section, showing a detail 35 portion of a shoe and the slide in superior position when in use; Fig. 3 is an end view of the shoe, the position of the slide corresponding with that shown in Fig. 2, and Fig. 4 is a perspective view of the slide.

40 In the drawings A represents a low-cut shoe having the back of its counter portion constructed with three plies of material termed the quarter B, the stiffening counter C and the counter lining D, all of ordinary 45 construction. These parts are secured together in the usual manner at or near their upper edges by means of the seam E, and the stiffening counter terminates a short distance below said seam, so as to leave the edge at 50 the seam flexible.

55 My invention is applied to the counter portion of the shoe and comprises what I have chosen to term as before stated a slide D made of thin sheet metal or other suitable material forming a substantially rigid plate having a flat pull arm 2 which is adapted to

be held between the thumb and forefinger at the handle portion 3 when pulling on the shoe. The slide also has a pair of side wings 4 and 5 integral with the pull arm and assuming a curved form similar to the circular or curved inner surface of the heel of the shoe when in the position shown in Fig. 1. The slide is shown placed between the counter and the quarter where it is free to move 60 up and down. It may be placed between the counter and counter lining when desired. The stitching of the seam E around the upper edge of the plies at the heel of the shoe is left open to allow the pull arm to extend 65 above the counter when in use. The quarter is notched at 6 so that when the slide is in lowered position the handle portion of the pull arm recedes substantially flush with the seam E. 75

The curvature of the wings conforming with the heel when in lowered position, causes the sides of the shoe to expand slightly when the slide is in superior position as shown in Fig. 3, thus extending the opening 80 of the shoe so that the foot can be more readily inserted therein. The inner surface of the pull arm forms a guide for the heel of the foot and acts as a shoe horn. The wings of the slide stiffen the upper edge of 85 the heel of the shoe when in superior position, and provide a smooth and rigid surface for guiding the heel of the foot into the shoe.

In accordance with the patent statutes, I have described the principle of operation of 90 my invention, together with the construction which I now consider to represent the best embodiment thereof, but I desire to have it understood that the construction shown is only illustrative and that the invention can 95 be carried out by other means and applied to uses other than those above set forth, within the scope of the following claims.

Having described my invention, what I claim as new and desire to protect by Letters 100 Patent, is:—

1. A device of the class set forth, comprising in combination with a low-cut shoe, having the back of its counter portion formed by a plurality of plies of material, a slide 105 freely disposed between said plies and having a pull arm extending above the upper edge of said counter portion and a lateral wing on its lower portion forming a stiffening means between the plies for the upper edge 110 of the shoe when the slide is in superior position.

2. A device of the class set forth, comprising, in combination with the back of the counter portion of a low-cut shoe, a slide embedded in and having an arm extending above said back and a pair of lateral wings on its lower portion adapted when in superior position to expand said back and reinforce its upper edge.
3. A device of the class set forth, comprising, in combination with a shoe having the back of its counter portion provided with a plurality of plies of material, a slide between said plies having a pair of curved wings, and a pull arm extending from said wings and above said plies, for the purposes specified.
4. A device of the class set forth, comprising,

ing, in combination with a low-cut shoe having the back of its counter portion formed by a quarter, a stiffening counter, a counter lining, and a seam at the upper edge of said quarter and having an opening, a slide between said quarter and counter having a pull arm extending through said opening by which the slide can be raised and lowered, for the purposes specified.

25

In testimony whereof, I have signed my name to this specification, in the presence of two subscribing witnesses.

WORTHINGTON S. TELFORD.
